US00D851642S

(12) **United States Design Patent** (10) **Patent No.:** **US D851,642 S**
(45) **Date of Patent:** **** Jun. 18, 2019**

(54) **ADJUSTABLE COMPUTER MOUSE**

(71) Applicant: **CONTOUR DESIGN, INC.**, Windham, NH (US)

(72) Inventors: **Steven Wang**, Windham, NH (US); **Andrew David Morgan**, Derry, NH (US)

(73) Assignee: **CONTOUR DESIGN, INC.**, Windham, NH (US)

(**) Term: **15 Years**

(21) Appl. No.: **29/671,387**

(22) Filed: **Nov. 27, 2018**

Related U.S. Application Data

(62) Division of application No. 29/601,243, filed on Apr. 20, 2017, now Pat. No. Des. 834,576.

(57) **CLAIM**

The ornamental design for an adjustable computer mouse, as shown and described.

DESCRIPTION

FIG. 1 is a perspective view of an embodiment of the adjustable computer mouse;

FIG. 2 is a top view of the embodiment of the adjustable computer mouse;

FIG. 3 is a bottom view of the embodiment of the adjustable computer mouse;

FIG. 4 is a rear view of the embodiment of the adjustable computer mouse;

FIG. 5 is a front view of the embodiment of the adjustable computer mouse;

FIG. 6 is a right side view of the embodiment of the adjustable computer mouse; and,

FIG. 7 is a left side view of the embodiment of the adjustable computer mouse.

1 Claim, 7 Drawing Sheets
